FUSIBLE CONNECTING TERMINAL

Constantine P. Xenis, Little Neck, Long Island, N. Y., assignor to Consolidated Edison Company of New York, Inc., New York, N. Y., a corporation of New York

Application September 21, 1939, Serial No. 295,992

14 Claims. (Cl. 200—133)

This invention relates to fusible terminal connecting means of the general type, wherein a cluster of limiter elements of fusible character are interposed between an electrical bus bar or equipment terminating detail and the cables to be attached thereto. The limiter elements used in this invention are of similar type and for similar purposes as the limiter elements disclosed in my prior application for patent, filed June 6, 1939, and bearing the Serial No. 277,741.

One important object of the present invention is to provide a cluster of interconnected limiter elements, each having an individual cable attaching means.

16 A further important object of the present invention is to provide an arc-proof shell of novel construction for enclosing these limiter elements and so arranged that a separate arcing chamber is provided for each fusible element.

20 Another important object of the invention is the provision of a completely insulated cluster of limiters interconnected and formed with an integral extension projecting beyond the insulation and forming a connection to a bus bar or electrical apparatus terminal detail.

25 Another important object of the invention is to provide a novel assembly of such a device completely insulated and water-proofed and arranged to provide an easy arrangement for tapping the joints between the individual branch cables and the terminal connectors.

With the above and other objects in view, the invention consists in general of certain novel details of construction and combinations of parts 35 hereinafter fully described, illustrated in the accompanying drawings, and particularly pointed out in the claims.

In the accompanying drawings, like characters of reference indicate like parts in the several 40 views, and

Figure 1 is a plan view of one form of the completely assembled device before connection of the cables.

45 Figure 2 is a part elevation, part section on the line 2—2 of Figure 1, and also showing one form of supporting means for the device and the means for attaching the device thereto.

Figure 3 is a section on the line 3—3 of Figure 50 1 and showing a second form of support and attachment.

Figure 4 is a reduced section on the line 4—4 of Figure 1 but showing one cable connected to the device.

55 Figure 5 is an enlarged perspective view of the

base or main portion of the shell used in connection with this invention.

Figure 6 is a similar view of the top or complementary portion of the shell.

Figure 7 is a perspective view of a partially 5 assembled cluster of limiter elements showing a means of interconnecting these elements and the integral extension or stud.

The main portion 10 of a shell includes a generally rectangular body 12, having its vertical 10 and bottom edges rounded off. Projecting upwardly from opposite sides of the body 12 is a low wall portion 13, the inner faces 14 of which merge into the upper face 15 by curved portions 16. Extending up from the walls 13 are segments 15 frusto-conical bosses 17, one for each branch cable connection provided in the terminal, the inner or opposed faces 18 of which form upwardly extending continuations of the walls 14. Formed in the face 15 of the body 12 is a longitudinally extending groove or recess 19 located centrally between the walls 13. The bottom of this groove 19 is extended outwardly on opposite sides adjacent each end as at 20, and these outwardly extending portions terminate outwardly 25 at centrally slotted walls 21. A channel 22 is formed in the face 18 of each boss 17, and these channels terminate downwardly in recesses 23 which extend slightly below the bottom of the groove 19. A groove 24, serving to isolate limiter 30 elements thermally from the shell portions, is formed centrally of the bottom wall of each channel 22. A circular opening 25 extends vertically through the body at the center thereof, and screw receiving openings 26 are provided on each side 35 of the opening 25.

The upper or complementary part 11 of the shell consists of a body 27 having its longitudinal bottom edges rounded as at 28. The width of the body 27 is such that it fits snugly the walls 40 13 and the rounded edges 28 conform to and fit the rounded portions 16 of the member 10. Also, when the shell parts are assembled, the upper face of the body 27 lies flush with the upper faces of the walls 13. Segmento-frusto-conical bosses 45 29 extend upwards from the side portions of the body 27, and their outer faces 30 engage the boss faces 18 when the parts are assembled, so that each two bosses 17 and 29, when assembled, form a complete frusto-conical base having an opening 50 extending downwardly from its top. Screw holes 31 are provided in the body 27 and are positioned to register with the holes 26. Inclined channels 32 are formed in the lower parts of the bosses 29 and extend downwardly to the bottom of the 55

body 27. The shell portions 10 and 11 are molded from a non-conductive and arc-proof material, such as a composition of cement and asbestos.

Seated in the groove 19 is a conducting bar 33 having notches 34, which in the preferred embodiment of the invention are each located between an opposed pair of bosses 17. In each notch is seated the central portion 35 of a thin strip of conductive material, such as copper, the portion 35 being secured in place by silver solder or the like. From each end of the portion 35, the strip extends outwardly and is curved upwardly as at 36, the parts 36 forming fusible or limiter elements and being properly tapered in the manner shown in my aforesaid prior application to have a suitable temperature gradient. At the upper ends, the parts 36 merge integrally into wide strips 37 which fit in the channels 22 and project above the bosses to carry cable connector sockets 38.

Beneath the bottom of the member 10 is located a nut 39, and through the openings 31 and 28 extend screws 40, which screw into threaded openings 41 formed in the nut 39. The nut 39 is provided with a central threaded opening 42 wherethrough is screwed the threaded upper end 43 of an extension integral with the conducting bar. As shown in Figures 2 and 4, the extension is reduced at its lower end 44, while in Figure 3 the lower end of the extension is threaded as at 45. A rubber jacket 46 is molded around the sides, top and bottom of all parts of the assembly so that the shell is not only electrically insulated, but the jacket also covers the joint between the two parts of the shell, and thus renders the device water-tight. The jacket 46 also incloses the nut 39.

A terminal detail 54 serves to connect the under-cut portion 44 of the extension 43 to an electrical bus bar, switch terminal, transformer terminal or the like.

As another method of mounting the device, the structure shown in Figure 3 may be employed. In this case, a washer 55 engages against the bottom of the boss 49 and is held in position by a nut 56, screwed on the threaded end 45 of the extension. The extension passes through a suitable opening 57 in a bus bar 58, and a second nut 59 clamps the bus bar firmly between it and the nut 56, the bus bar itself being heavy enough to support the fusible connecting terminal.

In connecting a cable to one of the terminals, the arrangement shown in Figure 4 is preferably employed. As there shown, the end of the cable 60 is stripped of insulation, as at 61, and inserted in the socket 38 where it is secured by suitable means. In the preferred embodiment, the indented compression type connection is used. Asbestos tape 62 is then applied around the socket 38 and the projecting end of the member 37 to provide a smooth surface of uniform diameter with the upper end of the boss. The joint is then wrapped with rubber tape 63 which is carried from the insulation of the cable down over the portion of the jacket which covers the boss and the rubber tape is similarly covered with friction tape 64. Thus no water or moisture can enter the shell and short circuiting is prevented.

What is claimed is:

1. In a fusible terminal connecting means comprising a terminal supporting shell, including a main shell member and a complementary shell member, and means for securing said mem-

bers together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses.

2. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, and with clearance grooves formed in the bottoms of said channels.

3. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, said main shell member having a conducting bar receiving groove extending longitudinally between said recesses and being provided with passages, each leading from the conducting bar groove to a respective recess.

4. In a fusible terminal connecting means, comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, and with clearance grooves formed in the bottoms of said channels, said main shell member having a conducting bar receiving groove extending longitudinally between said recesses and being provided with passages, each leading from the conducting bar groove to a respective recess.

5. In a fusible terminal connecting means, comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first

- bosses and fitting thereagainst, the bosses of one of said members being provided with channels communicating with said recesses, said main shell member having a conducting bar receiving groove extending longitudinally between said recesses and being provided with passages, each leading from the conducting bar groove to a respective recess, and a rubber jacket surrounding both shell members except at the upper faces of said bosses.
6. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, and with clearance grooves formed in the bottoms of said channels, said main shell member having a conducting bar receiving groove extending longitudinally between said recesses and being provided with passages, each leading from the conducting bar groove to a respective recess, and a rubber jacket surrounding both shell members except at the upper faces of said bosses.
7. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, said main shell member having a conducting bar receiving groove extending longitudinally between said recesses and being provided with passages, each leading from the conducting bar groove to a respective recess, in combination with a conducting bar fitting in said groove, conductor members crossing said conducting bar and electrically connected thereto, said conductor members having portions at opposite sides of the conducting bar constituting limiter elements, terminal conductors formed integrally with the outer ends of said limiter elements and extending up said channels to project above the bosses, cable attaching means carried by the upper ends of the terminal conductors, and an extension electrically engaged with said conducting bar and extending outwardly of said shell.
8. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, and with clearance grooves formed in the bottoms of said channels, said main shell member having a conducting bar receiving groove extending longitudinally between said recesses and being provided with passages, each leading from the conducting bar groove to a respective recess, and a rubber jacket surrounding both shell members except at the upper faces of said bosses, in combination with a conducting bar fitting in said groove, conductor members crossing said conducting bar and electrically connected thereto, said conductor members having portions at opposite sides of the conducting bar constituting limiter elements, terminal conductors formed integrally with the outer ends of said limiter elements and extending up said channels to project above the bosses, cable attaching means carried by the upper ends of the terminal conductors, and an extension electrically engaged with said conducting bar and extending outwardly of said shell.
9. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, said main shell member having a conducting bar receiving groove extending longitudinally between said recesses and being provided with passages, each leading from the conducting bar groove to a respective recess, and a rubber jacket surrounding both shell members except at the upper faces of said bosses.
10. In a fusible terminal connecting means comprising a terminal supporting shell including a main shell member and a complementary shell member, and means for securing said members together, said main shell member having a lower body portion provided with terminal receiving recesses and having opposed pairs of upstanding bosses, said complementary shell member having a lower body portion shaped to fit on the main member between the bosses and having pairs of bosses complementary to the first bosses and fitting thereagainst, the bosses of one of said members being provided with channels communicating with said recesses, said main shell member having a conducting bar receiving groove extending longitudinally between said recesses and being provided with passages, each leading from the conducting bar groove to a respective recess, and a rubber jacket surrounding both shell members except at the upper faces of said bosses, in combination with a conducting bar fitting in said groove, conductor members crossing said conducting bar and electrically connected thereto, said conductor members having portions at opposite sides of the conducting bar constituting limiter elements, terminal conductors formed integrally with the outer ends of said limiter elements and extending up said channels to project above the bosses, cable attaching means carried by the upper ends of the terminal conductors, and an extension electrically engaged with said conducting bar and extending outwardly of said shell.

5 nected thereto, said conductor members having portions at opposite sides of the conducting bar constituting limiter elements, terminal conductors formed integrally with the outer ends of said 10 limiter elements and extending up said channels to project above the bosses, cable attaching means carried by the upper ends of the terminal conductors, and an extension electrically engaged with said conducting bar and extending outwardly of said shell.

11. In a limiter device, a conducting bar having transverse grooves on one longitudinal face, narrow conductor elements seated in said grooves and each projecting on opposite sides of said bar, 15 said conductor elements being fixed to said bar and the projecting portions being formed to constitute fusible limiters, enlarged ends on said elements, and cable sockets carried by said enlarged ends.

20 12. In a limiter device, a conducting bar having transverse grooves on one longitudinal face, narrow conductor elements seated in said grooves and each projecting on opposite sides of said bar, said conductor elements being fixed to said bar 25 and the projecting portions being formed to constitute fusible limiters, enlarged ends on said elements, cable sockets carried by said enlarged

ends, and an extension electrically engaging said bar.

13. In a fusible terminal connecting means comprising a cluster of limiter elements, the outer end of each element having means for attaching a cable, all limiter elements interconnected and an extension attached at the point of interconnection, insulating means encasing the limiter elements, their point of interconnection, and the extension, the outer end of the extension and the 10 outer ends of the limiter elements where cables are to be attached being free of insulation.

14. In a terminal connecting means comprising a cluster of conducting elements extending from a point of interconnection, each conducting element including cable attaching means at its end and a limiter or fusible element between the cable attaching means and the point of interconnection, integral means of connecting this point of interconnection to external electrical bus bars 20 or equipment terminal details, a sectional arc-proof body enclosing the conducting elements and provided with an arcing chamber and baffles adjacent each chamber, and insulation encasing the arc-proof body.

25

CONSTANTINE P. XENIS.
